GAME APPARATUS

Harry E. Williams and Lyndon A. Durant,
Chicago, Ill.

Application December 19, 1939, Serial No. 310,058

12 Claims. (Cl. 273—121)

This invention relates to amusement apparatus, particularly the so-called pin ball or bagatelle games, and has for its principal object the provision of a novel score control mechanism including a confined ball on the playboard and mechanism for automatically causing the ball to move back and forth when a certain score has been achieved, there being score indicating and control mechanism actuated by the confined ball 10 in a certain manner.

Viewed from another aspect, it is an object of the invention to provide, in a pin ball game or like apparatus having a ball playing board with certain score objectives thereon, such for example 15 as ball-operated switches in ball pockets, novelty score control means comprising a ball confined in a pen on the top of the board and electromagnetic means beneath the board for causing the ball to move back and forth in the pen when a 20 certain score objective is obtained, together with a score indicating board, and a stepping switch actuated by the ball each time the same moves across the pen, to register a score depending upon 25 the value of the particular objective obtained, and means for automatically stopping the confined ball when the appropriate score has been indicated.

A further object is the provision of a novelty 30 control device in the nature of a pen mounted on the top side of the ball playing board and adapted to confine a magnetically attractable ball free to move back and forth between the opposite 35 ends of the pen, magnetic means arranged beneath the board, and switch means situated approximately midway between the ends of the pen for operation by the ball to break the circuit for the magnetic attracting means periodically and thereby effect the back and forth movement of 40 the ball, said switch means also being adapted for connection in a score control circuit.

Yet another object is the combination of the 45 foregoing novelty control device with various score objectives or ball switches on the playboard and severally actuated by skillful playing 50 of the game such that different objectives or pockets will have different values and cause the confined ball to be moved back and forth a certain number of times depending upon that score value, together with score indicating means operably controlled by the ball-operated switch.

Other objects, advantages and novel aspects of the invention reside in certain details of construction as well as the cooperative relationship 55 of the component parts of the illustrative em-

bodiment described hereinafter in view of the annexed drawings, in which:

Fig. 1 is a fragmentary perspective of a pin ball game showing the confined control ball;

Fig. 2 is an enlarged fragmentary section along line 2—2 of Fig. 1, showing the magnetic ball moving means and ball restoring means for the regular score pockets;

Fig. 3 is a fragmentary longitudinal section through the ball pen and driving magnet taken along line 3—3 of Fig. 2;

Fig. 4 is a plan view of the switching mechanism; and

Fig. 5 is a circuit diagram.

Referring to Fig. 1, a preferred form of amusement apparatus in which the invention has been successfully incorporated includes a ball playing board 10 on which are situated a number of objectives or ball pockets 11, 11a, 11b, etc. At one side of the board is a projecting alley 12 up which playing balls are projected by any suitable means for movement onto the playboard with the object of lodgment in one of the pockets 11. The projecting means is not illustrated, since such devices are commonly known in the art and do not form per se part of the present invention. At the rear of the playboard is a score indicating panel 13 with suitable score indicating indicia 14 delineated thereon and adapted to be illuminated by electric lamps situated behind corresponding numbers and adapted to be illuminated by certain control mechanism described hereinafter and operated dependently upon the lodgment of a ball in one or another of the score pockets 11, 11a, etc.

The novelty control means constituting the principal feature of the present invention is so called because it combines the visual effect of the movement of a confined ball back and forth with the visual effect of illuminated lamps on the score control panel, there being an element of entertainment, interest fixation, and fascination in watching the control ball oscillate back and forth in its pen and correlating the movement of this ball with the fluctuating illumination of the lamps in the score control panel.

The novelty control means includes the provision on the playboard 10 of means for confining the control ball for movement in a predetermined path, said means in the present instance comprising the provision of a pair of parallel rails 15 extending preferably transversely of the board (the latter being tilted downwardly from the panel 13 in most games), there being bumpers 55

- 16 provided at opposite ends of the alley or pen defined by the rails. A magnetically attractive ball 17 is confined between the rails and is free to move back and forth against the bumpers 16.
- 5 A guard rail 18 is disposed on the uppermost side of the pen to prevent arrest of the playing balls and assure movement thereof toward the scoring pockets.
- Means for effecting movement of the confined 10 ball in the pen includes the provision of an electromagnet 19 (Figs. 2 or 3) mounted beneath the board with its core or armature 20 situated midway between the ends of the pen, the winding of the magnet being adequate to set up a magnetic field strong enough to attract the ball to the core from an extreme position at either end of the alley or pen. A control button 21 is disposed at the mid point in the pen for engagement and depression by the ball 17 when attracted by 15 the magnet to close a control switch 22. This switch, as will appear in the description of the circuit diagram hereinafter, is arranged to effect an opening of the energizing circuit for the magnet so that the ball may move off the button 21 by the combined restorative action of the same coacting with the spring arm of switch 22 which holds it in normally raised condition, and the momentum gained by the ball in being attracted 20 onto the button.
- 30 The score objectives 11, 11a, etc., each include a ball-operated control device, such for example as the leaf spring switches 23, 23a, 23b, which are normally open and adapted to be closed by a ball dropping into the corresponding pocket.
- 35 Any well-known means may be provided for effecting removal of the balls from the score pockets, the present embodiment by preference employing kick-outs each comprising an arm 24 attached to the plunger 25 of a solenoid 26 mounted beneath the board adjacent each of the score pockets, the solenoids being energized to effect raising movement of the arms 24, which lifts the ball in the corresponding pocket out of the latter for gravitation down the playboard to be reused.
- 40 The circuit connections and cooperating switching means employed in conjunction with the novelty control device includes a commutating or limit switch generally indicated at 30 in the circuit diagram of Fig. 5. The commutating 45 or limit switch employed in the present arrangement is provided with three banks of contacts 31, 32 and 33, each corresponding to one of the score pockets 11, 11a or 11b. Bank 31 is connected by a conductor 31a to one terminal of the score switch 23 corresponding to the score pocket 11, the other side of this score switch, along with one terminal of each of the remaining score switches, being connected by a common conductor 35 to one terminal of a battery 36. Similarly, the remaining two banks 32 and 33 are connected by common conductors 32a and 33a to the corresponding score switches 23a, 23b, and the remaining terminal of the battery 36 is connected to a common conductor 37.
- 50 Each bank of commutator contacts is provided with a wiper connected in common by conductor 38 to one terminal of a holding relay 39, the remaining terminal of which is connected by conductor 40 to one contact of a spring switch with a normally closed contact 41 connected to the common battery return 37. Thus, when any of the score switches is closed by a ball dropping into a pocket, a power circuit will be closed through one of the commutator banks 31, 32, 33 55 to energize the holding relay 39, and this relay

will close contacts 42 (switch A, Fig. 4), thus connecting battery from feeder 35 to the ball attracting magnet winding 19, the opposite terminal of which is connected through a normally closed switch 43 in circuit with the battery return conductor 37.

The ball attracting magnet 19 having been energized as aforesaid, the magnetically attractive ball 17 will be attracted to the button 21, the combined weight of the ball and force of attraction of the field of the magnet, causing the switch 22 to be closed, thus connecting battery through switch 42 to one terminal of the step-up delay magnet 44, circuit to which is completed from its remaining terminal to the battery return conductor 37. Operation of the delay magnet 44 closes a switch 45, as indicated by dotted lines, thus connecting battery from conductor 35 to the strapped terminals of the score step-up magnet 54 and the commutator stepping magnet 46, 20 the return terminal of the score magnet being connected to the battery feeder 37 while the remaining terminal of the commutator magnet is connected to one terminal 47 of a normally open spring switch contact 48 (switch B, Fig. 4) (which is closed by holding relay 39) connected to the return side of the battery 37, thus causing the commutator wipers to be stepped around by action of a ratchet mechanism 46a (Fig. 4) driven by the step-up magnet or solenoid 46.

If a ball has been lodged in pocket 11, having an assigned score value of 1000 points, the switch 43 (D in Fig. 4), as indicated by the dotted line arrow in Fig. 4, is normally closed (see Fig. 5 also) and will be opened each time the magnet 35 44 is energized, thus opening the circuit to the ball attracting magnet 19 momentarily, with the result that the combined restorative action of the ball-operated control switch 22 in restoring button 21 to raised position, and the momentum of 40 the ball, will assure that the ball moves away from the button 21 so that switch 22 will again open, thus deenergizing the delay magnet 44 and the stepping magnet 46, which immediately restores switch 43 to closed circuit condition so 45 that the ball magnet 19 is again energized with a consequent return of the ball onto the control button 21 and a repetition of the foregoing action of the delay and stepping magnets. The delay magnet 44 is regulated to release slowly enough 50 to give the ball time to move a substantial distance away from the button before being attracted again.

From this description, it will appear that each time the ball is attracted to engage the button 55 21, the commutator switch is stepped once, but since there are a different number of contacts in each of the banks 31, 32, and 33, the number of times the commutating switch will step will depend upon which of the scoring switches 23, 60 23a, etc., is closed by the ball. In this manner the different score values of the various pockets are accounted for.

The score indicating means includes a bank of lamps 50 each having one terminal connected 65 in common to the battery feeder 37 and each having its remaining terminal connected to one of the contacts 51 in the contact bank of score switch generally indicated at 52 in Fig. 4, this switch also being a stepping switch similar to 70 the commutator switch 30 and having a wiper contact arm 53 connected to the other battery feeder 35. Thus, energization of the stepping magnet 54 of the score switch will cause wiper 75 53 to move successively into engagement with the 75

contacts 51 to illuminate one or another of the lamps 50 which are situated behind the score panel 13.

Switch 45, as indicated by the dotted line arrow in the circuit diagram, is operated by the step-up delay coil.

The stepping magnet 54 of the score switch, it will be recalled, is energized by action of switch 45 each time the ball switch 23 is closed, and the number of times the score switch will step will therefore be determined by which bank of contacts 31, 32 or 33 has been connected by lodgment of a playing ball in one of the score pockets to step the commutator switch; but since the number of contacts in each bank of the commutator switch is different, it will be apparent that the score switch will be stepped a different number of times depending upon the score value of the particular pocket into which the playing ball has been lodged.

A peculiarity of the commutator switch is that it is restored to zero position after each scoring operation while the score switch remains in whatever advanced position it may have been moved to. The restoration of the commutator switch is accomplished automatically by virtue of the fact that as soon as the wiper in either of banks 31, 32 or 33 moves off the last contact, the energizing circuit to holding relay 39 is broken, with the result that contact arm 48 falls back to engage contact 49 and connect battery from conductor 37 to one terminal of a commutator reset solenoid 60, the remaining terminal of which is connected through a normally open zero-break switch 61 to the other battery terminal, switch 61 being normally held open by a pin 62 on the ratchet means 46a when the latter is in its initial or zero position, switch 61 closing when the commutator switch makes even one step from initial position, and remaining closed until magnet 60 is energized for the purpose of restoring the commutator switch to its zero position. Both the score and commutator switches employ spring means tensioned by stepping of the switch-
es away from initial position and effective to restore the wipers to such position when a suitable latching pawl is released by action of the magnet 60, for example, in the commutator switch.

50 The score switch is reset to zero condition by energization of its resetting solenoid 65, one terminal of which is connected to common battery conductor 37 and the other terminal of which is connected through a manually controlled switch 66 adapted to be closed by operation of a coin slide 67 or other master control device associated with the game apparatus.

Detailed statement of operation

60 Assuming that the game apparatus is in the condition shown in the several figures and the player projects a playing ball up the alley 12 and a ball migrates into the opening 11, the cor
65 responding ball switch 23 (Fig. 5) will be closed and connect battery from conductor 35 through the first contact of contact bank 31 to the rotary wiper and thence via conductor 38 through the winding of holding relay 39, conductor 40, switch 70 41, to return to battery via conductor 37, thus causing relay 39 to pull up and close switches 42 and 43.

As a result of the closure of switch 42 by the holding relay, battery is connected through the 75 commutator switch to one side of the ball at-

tracting magnet 19 and through the closed switch 43 (D) to battery return 37, thus energizing the magnet 19 and attracting the ball 17 onto button 21, with a resultant closure of switch 22, which in turn connects battery to the step-up delay solenoid 44, in consequence of which switches 43 and 45 (D and C) are respectively opened and closed. Opening of switch 43 breaks the ball magnet circuit, with a consequent opening of switch 22 to the delay relay; meanwhile, closing of switch 45 (C) energizes solenoid 54 to step the score counter once, and solenoid 46 to step the commutator switch once (switch 48 (B) meanwhile having been closed by action of the holding relay 39). When the ball rolls off the button 21, switch 22 opens as aforesaid, and after a very short interval the delay solenoid 44 is released, again causing switch 43 to close to energize the ball attracting magnet which pulls the ball back onto the button with a repetition of the operation of the delay relay and the score and commutator switch solenoids, this action being repeated a number of times corresponding to the number of contacts in bank 31.

Should the ball have lodged in pocket 11b, instead, the same train of events would take place, with the exception that the score and commutating switches would be stepped a greater number of times owing to the larger number of contacts in bank 33. 30

As soon as the commutator wiper 30 passes the last contact in the bank energized by a scoring ball, holding relay 39 is released and switch arm 48 drops back to engage contact 49 and connect battery to the commutator reset solenoid 60, the zero break switch 61 being closed at this time and opened as soon as the ratchet pin 62 is restored to normal position against switch 61. 35

In order to dislodge the scoring balls from the pockets, the present arrangement provides for the closing of switch 41 by the momentary operation of the resetting solenoid 60 and associated restoring mechanism, switch 41 connecting battery to the three kick-out solenoids 26, 26a, 26b, thus throwing any and all balls out of the scoring pockets. The score which has been set up on the panel 13 may be cleared by operation of the master control 61 to close switch 66 and energize solenoid 65, which will release the ratchet mechanism of the score switch for restoration by its spring means to zero position. 50

The various advantages and objects of the invention may be accomplished by modifications of the particular embodiment specifically described herein, and it is intended that the appended claims shall include all equivalent arrangements fairly coming within their call. 55

Having thus described our invention, what we claim as new and desire to protect by Letters Patent is:

1. In an amusement apparatus including a ball playing board and means for playing balls thereon, together with a score objective to be attained by playing one or more of said balls in a certain manner, novelty score control means comprising a magnetically attractable control ball, and means confining the same for limited movement in a predetermined area on said board, electromagnetic means for effecting movement of said magnetically attractable control ball back and forth in said area, score objective means operably controlled by a ball played on said board for energizing said electromagnetic means, score indicating means and switching mechanism operably associated with said score objective means for 75

- effecting energization of said electromagnetic means to cause movement of said control ball different amounts depending upon which score objective is achieved as aforesaid, and switching 5 means operatively controlled by said ball in the movement thereof for operating said score indicating means to indicate a score corresponding to the particular score objective obtained.
2. In an amusement apparatus including a ball 10 playing board and means for playing balls thereon together with ball scoring pockets in which playing balls are to be lodged in playing the game, novelty control means comprising, in combination, a score switch operatively associated 15 with each score pocket, a ball pen on said board, a magnetically attractive control ball arranged for movement back and forth in said pen, electromagnetic attracting means situated to attract said control ball to a certain position in the pen, 20 a switch operated by said ball in the pen at said certain position, said score switches being connected in a circuit to energize said attracting means when a ball is lodged in a score pocket, means actuated by said switch operated by the 25 magnetically attractive control ball to deenergize said attracting means momentarily, means for causing said control ball to move away from said certain position after deenergization of the attracting means, and impulse-operated switch- 30 ing mechanism operably controlled by said switch which is actuated by the control ball.
3. In an amusement apparatus including a ball playing board and means for playing balls thereon together with ball scoring pockets in which 35 playing balls are to be lodged in playing the game, novelty control means comprising, in combination, a score switch operatively associated with each score pocket, a ball pen on said board, a magnetically attractive control ball arranged 40 for movement back and forth in said pen, electromagnetic attracting means situated to attract said control ball to a certain position in the pen, a switch operated by said ball in the pen at said certain position, said score switches be- 45 ing connected in a circuit to energize said attracting means when a ball is lodged in a score pocket, means actuated by said switch operated by the magnetically attractive control ball to deenergize said attracting means momentarily, 50 means for causing said control ball to move away from said certain position after deenergization of the attracting means, and impulse-operated switching mechanism operably controlled by said switch which is actuated by the control ball, 55 said switching mechanism being arranged and constructed to be impaled a different number of times depending upon which score switch has been operated and to effect deenergization of said electromagnetic attracting means at the ter- 60 mination of said predetermined number of impulse operations corresponding to the particular score switch operated by lodgment of a ball in a particular pocket, together with score indicating mechanism operably controlled by the 65 switch actuated by the control ball in the pen, and means coacting with said switching mechanism for restoring the same to an initial condition after each operation thereof by lodgment of a ball in a particular pocket.
- 70 4. In a ball game apparatus including a playing board and means for projecting balls on said board for movement into one of a plurality of score pockets, novelty score control mechanism comprising, in combination, a score switch oper- 75 atively associated with each score pocket for operation by a ball lodged therein, an elongated confined runway on said board, a magnetically attractive control ball in said runway, electro- 5 magnetic means arranged to attract said ball toward the middle of the runway, a control switch arranged in said runway for operation by a control ball when attracted as aforesaid, an electrically operable stepping switch including a number of common contacts in banks, there being as many banks as there are score pockets, 10 each of said score switches being connected with one of said banks in a power circuit for actuating said stepping switch, lodgment of a ball in one of said pockets effecting operation of the stepping switch a number of times corresponding 15 to the number of contacts in the corresponding bank, said stepping switch and said score switch means cooperating to effect energization of said attracting means, said switch operated by the control ball cooperating with said stepping 20 switch to effect stepping operation of the latter and intermittent deenergization of said attracting means whereby the stepping switch will step each time the ball is attracted, the number of steps depending upon which of said score 25 switches is operated as aforesaid, and score indicating mechanism operably controlled by said stepping switch.
5. In an amusement device including ball play- 30 ing means with ball pockets having assigned score values in which a ball is to be lodged by playing the game, score control means comprising in combination: a score switch operatively associated with each pocket, a ball pen arranged in view of the player, a control ball movable 35 back and forth in the pen, electrically actuated means for effecting said movement of the ball, a control ball switch actuated intermittently by the control ball moving as aforesaid, and impulse- 40 operated switching means in circuit with said ball moving means and each said score switch and arranged to be operated a different number of times determined by different score switches 45 cooperable with the operations of said control ball switch, and electrical score indicating means 50 operated in steps by cooperation of said control ball switch and impulse-operated switching means.
6. In an amusement device including ball play- 55 ing means with ball score pockets each having a different assigned score value and each pocket having a score switch operated by a ball therein, novelty score control means comprising, in combination, an electrically operated score indicator adapted to be operated in steps, a stepping score switch for operating said indicator, a ball pen, an electromagnetic ball in said pen, electromagnetic means for attracting said ball to a certain position in the pen, means cooperat- 60 ing with said attracting means for effecting move- 65 ment of said ball away from said position when not under the influence of said attracting means, and switching mechanism including a control ball switch situated adjacent said certain position for actuation each time the control ball is attracted as aforesaid, and an electrically operated limit switch connected in a circuit with each score switch, said control ball switch and said stepping score switch to cause said control ball to move to said certain position a number of times cor- 70 responding to the assigned score value of which- 75 ever score switch is operated, said stepping switch being stepped a corresponding number of times.
7. Apparatus as defined in claim 6 further characterized by the combination therewith of 75

electrically actuated means for automatically dislodging balls from score pockets at the conclusion of each operation of said stepping switch by lodgment of a ball in a score pocket.

5 8. Apparatus as defined in claim 6 further characterized by the provision of electrically controlled means for restoring said limit switch automatically to an initial starting condition subsequent to each operation thereof by lodgment 10 of a ball in a score pocket, whereby to condition the same for further operation when balls are lodged in additional score pockets.

9. In a game apparatus including a plurality of score pockets, each provided with a score switch 15 operated by a ball lodged in the pocket in playing the game, novelty score control means comprising a ball pen arranged in view of the player, a control ball in the pen, electrically actuated means including a control ball switch operative- 20 ly associated with the pen to be operated by the ball when moved into a certain position therein, means for effecting movement of the ball into and out of said position, and limit switch means connected in a circuit with said ball moving 25 means, said control ball switch and each of said score switches for operation a different number of times depending upon arbitrarily assigned values for each pocket and determined by connection of said limit switch means with a power 30 circuit by operation of a given score switch, for moving said ball back and forth in the pen a number of times corresponding to the arbitrary value of whichever score switch is operated.

10. Apparatus as set forth in claim 9 further 35 characterized by the combination therewith of an electrically operated visual indicator operable in steps, stepping switch means for operating said indicating means, and means operably controlled by said control ball switch for actuati-

ing said stepping switch a number of steps corresponding to the movement of the control ball as aforesaid.

11. Apparatus as set forth in claim 9 further characterized by the combination therewith of 5 an electrically operated visual indicator operable in steps, stepping switch means for operating said indicating means, and means operably controlled by said control ball switch for actuating said stepping switch a number of steps corresponding to the movement of the control ball as aforesaid, said limit switch means being of a type moved away from a starting position a number of steps depending upon the score value of the score switch actuated, and means controlled 15 by said limit switch for automatically restoring the same to starting position when it has operated the requisite number of steps following operation by any score switch.

12. In a device of the class described, nov- 20 elty score control means in the form of a ball runway, a magnetically attractable ball confined in said runway, electromagnetic means for attracting said ball to a predetermined position in the runway, means for effecting movement of 25 the attracted ball away from said position when said attracting means is deenergized, and switch means situated in the region of said predetermined position for actuation by said ball when attracted thereto, said switch means being adapt- 30 ed for connection in a control circuit, and means operably controlled by said switch means for effecting intermittent energization of said attracting means whereby said ball will be caused to oscillate relative to said position and effect in- 35 termittent operation of said switch means.
